CLOSURE OPERATOR

Edmund A. Rehwald, Rockford, Ill., assignor to
Barber-Colman Company, Rockford, Ill., a corporation of Illinois

Application September 28, 1946, Serial No. 700,079

12 Claims. (Cl. 74—37)

1

This invention relates to power driven operators for closures such as garage or factory doors, and has more particular reference to such operators in which the reciprocating motion to open and close the closure is effected by a unidirectionally rotatable electric motor.

The general object is to reduce substantially the cost of an electric motor closure operator, while at the same time providing an operator which is durable in construction and is adapted to actuate a closure with a smooth and substantially uniform motion even though the closure is not balanced accurately.

The foregoing object is achieved in part through the provision of a novel yieldable mechanical connection between an actuating element moved in an endless path and a reciprocating member connected to the closure to be operated.

Another object is to form the reciprocable member above referred to in two parts arranged for relative rotation in one direction only.

Still another object is to provide a novel quick detachable connection between the reciprocable member and the element which moves in the endless path.

Other objects and advantages of the invention will become apparent from the following detailed description taken in connection with the accompanying drawings in which:

Figure 1 is a side elevational view of a motor operator embodying the present invention and arranged to actuate a garage door.

Fig. 2 is a fragmentary side elevational view of the yieldable connection between the operator and the door.

Fig. 3 is a fragmentary plan view of the part shown in Fig. 2.

Fig. 4 is a perspective view of an overrunning clutch.

Fig. 5 is a detailed view of the parts forming the detachable connection between the door and the operator, these parts being shown in disengaged position.

Figs. 6, 7, and 8 are fragmentary perspective views showing the parts of the yieldable connection in different positions.

For purposes of illustration the improved motor operator is shown in the drawings applied to a garage door 10 of the overhead type and comprising a plurality of hingedly connected sections guided along sidetracks 11 for movement from a vertical position (Fig. 1) closing a door opening 12 to an overhead or horizontal position beneath a ceiling 13. The operator proper is mounted on

2

a frame 14 secured to the ceiling 13 and spaced rearwardly from the door opening.

A unidirectional electric motor 15 operates through speed reduction mechanism such as belts 16 to drive a vertical shaft 17 having a sprocket 18 fast on its lower end. This sprocket meshes with an endless chain 19 which extends to a position adjacent the door opening 12, where its other end meshes with a sprocket 20 rotatable on a vertical stud 21 which is supported by a bracket 22 secured to the building wall above the door opening. The chain carries an actuating element in the form of a vertical pin 23 secured to one link of the chain and depending therefrom so as to travel with the chain in an endless path defined by the sprockets 18 and 20 and the intervening straight runs of the chain.

The back and forth motion of the actuating pin 23 is imparted to the door through the intermediary of a car 24 of U-shaped cross section having upstanding sides which terminate in tubular guides 25 slidable along spaced rods 26. The latter are located above the chain 19 and at opposite ends are secured by clamps 27 to the bracket 22 and the motor frame 14. A vertical shaft 29 projecting through the car 24 and journaled in a bearing 30 thereon is formed at its lower end with a downwardly opening yoke 31 pivotally connected by a pin 32 to one end of an adjustable link 33. The other end of the latter is connected to the upper section of the door 10 which is thus opened and closed in the rearward and forward strokes of the car 24 between limit positions determined by abutment of the car with the clamps 27.

In accordance with the present invention, the motion of the actuating pin 23 on the chain is transmitted to the car 24 through a novel yieldable connection which permits the pin to travel with the chain around the sprockets 18 and 20 while the car and the door are dwelling in either limit position. Herein this connection includes an elongated horizontally disposed link 34 pivotally connected at one end of the pin 23 through a block 35 hinged on the link by a pivot 36 and having a hole 37 therethrough receiving the actuating pin when the block 35 is swung upwardly in a horizontal position as shown in Figs. 1 and 2. The block is urged into this position by a torsion spring 38 encircling the pivot 36. By prying the block 35 off from the pin 23 and swinging the block downwardly out of engagement with the pin as shown in Fig. 5, the door may be disconnected from the chain and the motor operator.

thereby permitting the door to be opened and closed manually.

Intermediate its ends, the link 34 has a lost motion connection with the car shaft 29, which connection is formed by projection of the shaft through a slot 39 of substantial length formed in and extending longitudinally of the link 34. The slack in this lost motion connection is normally taken up by a spring 40, which preferably is of the compression type and encircles and is supported by a rod 41 secured at one end to a depending flange 42 on the other end of the link 34. The rod projects loosely through and is guided in a cross hole 43 in an enlargement 44 of the shaft 29. Opposite ends of the spring 40 thus abut against the shaft enlargement and the link and 42 so that the motion of the actuating pin 23 is transmitted to the car 24 through a spring cushion which is adapted to yield in order to permit the pin to travel around each chain sprocket while the position of the car 24 remains fixed. In the present instance, the length of the spring 40 is somewhat greater than the spacing of the flange 42 and the shaft enlargement 44 when the shaft is at the end of the slot 39 farthest from the flange 42 as shown in Fig. 7. This arrangement insures that all slack in the lost motion connection will be taken up at all times.

In accordance with another aspect of the invention, an overrunning clutch device or one way ratchet is provided to prevent turning of the shaft 29 relative to the car in one direction while permitting free turning of the shaft and the link 34 in the other direction as the actuating pin travels around the chain sprockets. Herein this device comprises a helical spring 46 closely wound around a cylindrical nut 47 threaded on or otherwise rigidly secured to the upper end of the shaft 29 above the car 24. This spring frictionally grips the body of the nut while the lower end 49 is fastened by a screw 50 to the car 24. With this arrangement, clockwise turning of the shaft 29 as viewed in Fig. 3 will tend to unwind the spring permitting the shaft 29 to turn freely relative to the car. The spring is tightened, however, around the nut by reverse turning of the shaft, and the resulting frictional gripping of the nut by the spring locks the shaft and the link 34 against further turning relative to the car. By this action, the tendency of an unbalanced door to move back and forth relative to the continuously advancing actuating pin 23 is reduced, and in most instances substantially eliminated. The door is, therefore, moved, especially in the closing direction, with a smoother and less jerky motion even though it is connected to the actuating pin 23 by a readily yieldable connection.

The cycles of the motor 15 are started in the usual way by manual or automatic closure of a suitable switch (not shown), and are terminated in response to actuation of a limit switch 52 by either of two cams 53 (Fig. 3) fixed to the chain 19 at spaced points. The cams are positioned to actuate the limit switch as the actuating pin 23 starts around the corresponding sprocket (Fig. 6) when the door reaches its limit position, the motor and the chain motions being arrested when the actuating pin reaches the dead center position as shown in Fig. 3 or is disposed slightly beyond this position.

Assuming that the motor operator is at rest with the door closed, the parts will be positioned as shown in Figs. 1, 2, and 3, the shaft 29 being disposed in the near end of the slot 39 with the link 34 lying substantially parallel to the path of

the car 24. When the motor is started in the next door opening cycle, the actuating pin 23 moves farther around the sprocket 20, the link 34 turning around the shaft 29 and sliding relative to the latter to permit this motion.

In this motion, the distance between the actuating pin 23 and the shaft 29 is shortened as permitted by sliding of the shaft along the slot 39, this motion being assisted by the force of the spring 40. Thus, during the initial part of each cycle, there is no load on the motor 15, and the latter comes up to full running speed before any load is imposed, thereby permitting the use of an inexpensive low starting torque motor without danger of the latter being damaged in service use.

As the actuating pin approaches a position opposite the shaft 29, that is, when the link 34 extends transversely of the path of the car, the parts will then be disposed in the position shown in Fig. 7. Then in the further movement of the actuating pin, the link 34 slides reversely relative to the shaft 29 and, acting through the spring 40 applies the force of the operator to the car and the door to initiate movement of the latter. The shock of starting the door is thus cushioned by the spring which forms a yieldable connection for transmitting the motion of actuating pin 23 to the door to open the latter.

When the door reaches a limit position, for example, the closed position, the actuating pin 23 will have reached the sprocket 20 and started around the latter with the link 34 and the spring 40 in the relation shown in Fig. 6. The motor circuit is now opened by the cam 53 and the actuating pin 23 continues to travel around the sprocket 20 to the final position shown in Fig. 3. The car 24 and the shaft 29 now being stationary, the link 34 will move endwise relative to the shaft as permitted by further compression of the spring to the degree shown in Fig. 2.

By virtue of the simple and inexpensive yieldable link connection above described and the friction ratchet 46, it is possible to operate a heavy closure member such as a garage door smoothly and without a jerky motion in spite of the yield necessarily provided in order to permit the use of a unidirectional electric motor. The overall cost of the door operator is thus reduced substantially as compared to operators having reversible electric motors.

I claim as my invention:

1. A closure operator having, in combination, an actuating element movable along an endless path having straight sides and arcuate connecting ends, a car guided for reciprocatory movement back and forth between limit positions along a line disposed between said path sides, a shaft journaled on said car to turn about an axis perpendicular to the plane of said path and adapted for pivotal connection with a closure member to be operated, a link pivotally connected at one end to said actuating element and having a longitudinally elongated slot intermediate its ends receiving said shaft, and a resilient element acting in compression between the other end of said link and said shaft.

2. A closure operator having, in combination, an actuating element movable along an endless path, a car guided for reciprocatory movement back and forth in a line disposed between the sides of said path, a shaft journaled on said car to turn about an axis perpendicular to the plane of said path and adapted for pivotal connection with a closure member to be operated, a link pivotally connected at one end to said car actu-

ating element having a lost motion connection intermediate its ends with said shaft, and a resilient element acting in compression between the other end of said link and said shaft.

3. A closure operator having, in combination, an actuating element movable along an endless path, a car guided for reciprocatory movement back and forth within said path, a shaft journaled on said car to turn about an axis perpendicular to the plane of said path and adapted for pivotal connection with a closure member to be operated, a link pivotally connected to said car and having a lost motion connection with said shaft, and means resiliently connecting said link and said shaft.

4. A closure operator having, in combination, an actuating element movable along an endless path, a car guided for reciprocatory movement back and forth within said path, a member journaled on said car to turn about an axis perpendicular to the plane of said path and adapted for pivotal connection with a closure to be operated, and means providing a longitudinally extensible link connection between said member and said actuating element including a part resiliently yieldable longitudinally of the link.

5. A closure operator having, in combination, an actuating element movable along an endless path, a car guided for reciprocatory movement back and forth within said path, a member journaled on said car to turn about an axis perpendicular to the plane of said path and adapted for pivotal connection with a closure to be operated, a link connection longitudinally extensible and contractible and pivotally connected at spaced points to said actuating element and said member, and means associated with said connection and acting yieldably to cushion the endwise contraction of the connection.

6. A closure operator having, in combination, an actuating element movable along an endless path, a car guided for reciprocatory movement back and forth within said path, a member journaled on said car to turn about an axis perpendicular to the plane of said path and adapted for pivotal connection with a closure to be operated, means providing a resiliently yieldable and longitudinally extensible link connection between said member and said actuating element, and means providing an overrunning clutch connection between said car and said member permitting turning of said link connection relative to the car as said actuating element travels around the ends of said path but restraining reverse relative turning between said car and member.

7. A closure operator having, in combination, an actuating element movable along an endless path, a car guided for reciprocatory movement back and forth within said path, a member journaled on said car to turn about an axis perpendicular to the plane of said path and adapted for pivotal connection with a closure to be operated, means providing a resiliently yieldable and longitudinally extensible link connection between said member and said actuating element, and means connecting said car and said member to permit free relative turning of the two in one direction but restraining such turning in the opposite direction.

8. A closure operator having, in combination, an actuating element movable along an endless path, a car guided for reciprocatory movement

back and forth within said path, a member journaled on said car to turn relative to the latter in one direction, means restraining turning of said member relative to said car in the opposite direction, and means providing a resiliently extensible connection between said member and said actuating element.

9. A closure operator having, in combination, an actuating pin movable along an endless path, 10 a car reciprocable back and forth longitudinally of said path and adapted for connection with a closure to be operated, means providing a resiliently extensible and contractible link connection pivotally connected to said car, and a member 15 hinged on said link connection and adapted to interengage with said pin to connect the latter detachably to said pin.

10. A closure operator, having, in combination, an actuating element movable along an endless 20 path, a car reciprocable back and forth longitudinally of said path and adapted for connection with a closure to be operated, means providing a resiliently extensible and contractible link connection pivotally connected to said car, and 25 a member hinged on said link and adapted to interengage with said element and form a readily disengageable connection between said element and said car.

11. A closure operator having, in combination, 30 two spaced sprockets, an endless chain extending around said sprockets, a car guided for reciprocatory movement back and forth within said chain and adapted for connection with a closure to be reciprocated, a member journaled on said 35 car, a link connection between said member and a point on said chain, said member turning relative to said car while said point is traveling around one of said sprockets, and means constantly exerting a friction force resisting turning 40 of said member in at least one direction relative to said car.

12. The combination of, an endless chain having laterally spaced parallel sides and arcuate ends, sprockets supporting said chain and meshing with the latter at said ends, a unidirectional 45 electric motor driving one of said sprockets, a switch controlling the stopping of said motor, a car guided for movement back and forth between said chain sides, a member journaled on said car 50 and adapted for connection with a device to be reciprocated, a link connected at one end to said member and pivotally connected at the other end to a point on said chain whereby to permit said point to travel around the said sprockets while 55 said car dwells at the end of its stroke, and means carried by said chain and actuating said switch to stop said motor during said dwelling of the car and while said chain point is engaging said sprocket whereby to allow for idle travel of the 60 point after starting of said motor and before movement of said car is initiated.
